United States Patent Office

Des. 186,788
Patented Dec. 1, 1959

186,788

VENDING MACHINE CABINET

Anthony M. Caruso, New Bedford, Mass., assignor, by mesne assignments, to The Seeburg Corporation, a corporation of Pennsylvania

Application October 31, 1957, Serial No. 48,291

Term of patent 14 years

(Cl. D52—3)

Fig. 1.

Fig. 2.

Fig. 1 is a perspective view of the vending machine cabinet showing by new design; and

Fig. 2 is a top view thereof.

The undisclosed end of the vending machine is substantially the same in appearance as the end shown, and the rear is substantially plain.

I claim:

The ornamental design for a vending machine cabinet,
substantially as shown and described.
